UNITED STATES PATENT OFFICE.

JAN ARTHUR KUYSER, OF EDGEWOOD, PENNSYLVANIA, ASSIGNOR TO WESTINGHOUSE ELECTRIC AND MANUFACTURING COMPANY, A CORPORATION OF PENNSYLVANIA.

ARMATURE-WINDING.

1,382,987.

Specification of Letters Patent. Patented June 28, 1921.

Application filed April 16, 1913. Serial No. 781,443.

To all whom it may concern:

Be it known that I, JAN ARTHUR KUYSER, a subject of the ruler of the Netherlands, and a resident of Edgewood, in the county of Allegheny and State of Pennsylvania, have invented a new and useful Improvement in Armature-Windings, of which the following is a specification.

My invention relates to dynamo-electric machines, and it has special reference to means for interconnecting the armature coils of such machines.

One object of my invention is to provide means for reducing, as much as possible, a part of the load losses, that is, the copper eddy current losses, in dynamo-electric machines carrying conductors of comparatively large cross-section.

Another object of my invention is to provide means of the above-indicated character which shall be simple in form, inexpensive to construct and easy to install and repair.

Heretofore, in the operation of dynamo-electric machines having conductors of comparatively large cross section, heavy eddy currents occurred in the portions which were embedded in the iron, particularly if the conductors were made entirely solid. A means of partially overcoming the difficulty is to divide each complete conductor into several parallel conductors lightly insulated from each other. However, even when said means is employed, a large proportion of the load losses still remains.

According to my present invention, I provide a plurality of independent sets of special connectors for progressively, and in different combinations, connecting together the several parallel conductors or sections of which a single complete conductor is composed. The above-mentioned load losses are thereby practically eliminated, as will be understood from the following theoretical considerations.

As is well known to those skilled in the art, the voltage generated in a conductor varies throughout its depth. Consequently, local circuits are set up within the conductor which constitute a part of the "load losses." Hence, the old idea of sectionalizing the conductors. However, with the former usual plain interconnections between coils, much of the advantage gained by the sectionalizing was lost. I provide sectional-

ized end connectors between coils, and cause said connectors to join sections lying at different distances from the surface of the core member in accordance with a predetermined rule so that there is provided, through the winding, a plurality of separate paths, each of which includes the same number of active coil conductors, and in each of which there is generated the same total electromotive force. I thereby eliminate the greater portion of the eddy currents in the armature conductors and reduce the load losses to a negligible amount.

In the accompanying drawings, Figure 1 is a diagrammatic plan view, in development, of one complete group of armature coils conforming to my invention; Fig. 2 is a diagrammatic view showing solely my special end-connectors as applied to the coils of Fig. 1; Fig. 3 is a view, in longitudinal section, of a portion of a dynamo-electric machine embodying one form of connector that is used in my invention, Fig. 4 is a view in side elevation showing another associated form of end connector that is employed therein; and Fig. 5 is a distorted development embodying the application of the specific end connectors shown in Fig. 2 to a winding arranged as in Fig. 1.

Referring to the drawing, a plurality of coils 1 are disposed in the slots of the core 2 of a dynamo-electric machine 3, and have the usual overhanging and intercrossing end portions 4 which are supported in any suitable manner. Each coil 1 comprises a single conductor having a plurality of parallel sections 5, preferably lightly insulated from each other.

In order to obtain the above-mentioned progressive combinations of the sections 5 of the several coils 1, I employ a plurality of forms of end-connecting sets 6 and 7, respectively, which severally comprise a plurality of preferably insulated sections 8 equal in number to the sections 5. The connector sets 6 and 7 are severally attached, in any suitable manner, to the sectionalized ends 9 of the longitudinally adjacent overhanging portions 4 of predetermined pairs of coils. For instance, connecting-sleeves 10, suitably insulated from each other, may be employed. The system of connections may best be understood by reference to Figs. 1 and 2, in which a specific case is illustrated.

It will be understood, however, that I do not restrict my invention thereto, but that the invention is capable of much wider application.

5 In Fig. 1 a complete series group 11 of the coils 1 is shown as embodying twelve individual sectionalized coils 1 severally and progressively spanning a space of 23 slots on the core 2 of the dynamo-electric machine 10 3, and having their several sectionalized ends 8 connected according to Fig. 2 which is a developed sectional view of successive coil ends taken on line II-II in Fig. 3. The coils 1 are of one turn each and two 15 coils are disposed in each slot. The terminals 12 of the group 11 project outwardly for making connections to a machine terminal or to other corresponding groups of coils (not shown). The longitudinally-disposed 20 ends 9 of predetermined pairs of the intercrossing end portions 4 of the coils 1 are severally disposed in radial planes, as is customary. It will be seen that a repeating series of two of the end-connecting sets 6 25 and one of the end-connecting sets 7 is employed on the machine in question. Thus, each parallel path through the group 11 includes equal numbers—in this particular case three—of the various sections 5 of the 30 coils 1. The advantages of such a system of connections have hereinbefore been pointed out.

Referring to Fig. 5, the four conductors lying in the upper portions of the slots 1 to 35 12, inclusive, are indicated in the left hand portion of the diagram and, in like manner, the four conductors lying in the lower portions of the slots 23 to 34, inclusive, are indicated in the right-hand portion of the 40 diagram. The current-conducting lead 36 is subdivided into four component conductors which traverse the upper portion of the slot 1, reverse at the back of the armature and traverse the lower portion of the slot 45 23. In like manner, said four conductors successively traverse the upper portion of the slot 2, the lower portion of the slot 24, the upper portion of the slot 3 and the lower portion of the slot 25, performing a 50 simple reversal in the end connection in each instance. Between the conductors lying in the lower portion of the slot 25 and those lying in the upper portion of the slot 4, I insert one of my special end connectors 55 so that the upper conductor of the group lying in the lower portion of the slot 25 is connected to the upper conductor of the group lying in the upper portion of the slot 4, the remaining conductors performing a 60 simple reversal. A similar special end connector is inserted in the end connector associated with each third slot until the entire twenty-four slots in question are traversed and the four conductors are again 65 joined to the lead 37. Thus, it will be noted,

if the eight possible conductor positions in a slot be designated respectively as 1' to 8', inclusive, that each of the conductors traverses each of the positions 1' to 8', inclusive, three times. The course of a single conductor through the twenty-four slots is indicated by the solid circles in Fig. 5, whereas the remaining three conductors are indicated by line circles. Thus, the total reluctance of the magnetic paths interlinked with 70 each component conductor between the two main current taps is substantially the same, resulting in equal reactance for each of the four component conductors and, in this way, the production of unbalanced voltage and of 75 harmful circulating currents is prevented.

The diagram of Fig. 2 illustrates the invention in greatly simplified form, said diagram relating only to the front connectors and showing how, in every third slot, the 80 special connector is inserted in order to alter the depth of the immediately succeeding portion of each component conductor in the slots in which it may be embedded.

I do not wish to be restricted to the specific 90 structures and details herein set forth, but desire that only such limitations shall be imposed as are indicated in the appended claims.

I claim as my invention:

1. In a dynamo-electric machine, the combination with a slotted armature core member having an armature winding embedded in the slots thereof, said winding being provided with two current taps at points of opposite polarity, the portion of said armature winding included between said taps providing a plurality of distinct conducting paths said paths being provided by conductors traversing the same slots in the same order, 100 each of said conductors traversing different slots of said core member at different depths, the resultant reactance of all of said conducting paths being substantially equal.

2. In a dynamo-electric machine, a slotted 110 armature core member having an armature winding embedded in the slots thereof, said winding being provided with two current taps at points of opposite polarity, the portion of said armature winding included between said taps providing n distinct conducting paths, said paths being provided by conductors traversing the same slots of said core member in the same order, there being $2Kn$ conductors in each slot arranged 115 $2n$ conductors deep, K being any positive integer, each conductor traversing the same number of slots for each multiple of $\frac{1}{2n}$ th of the depth thereof.

3. In a dynamo-electric machine, the combination with a slotted armature core member having an armature winding embedded in the slots thereof, of two current taps to said armature winding at points of oppo- 130

site polarity, said armature winding providing a plurality of distinct conducting paths progressing around the armature in the same direction between said taps, each of said 5 paths constituting a conductor traversing a like number of said core slots at different depths, the sum of the depths of each conductor in all the slots traversed thereby being substantially equal.

10 4. In a dyanmo-electric machine, the combination with a slotted armature core member having an armature winding embedded in the slots thereof, of two current taps to said armature winding at points of opposite 15 polarity, said armature winding providing n distinct conducting paths between said taps, each of said paths constituting a conductor traversing the same m armature slots in the same order and said conductors being 20 arranged $2n$ deep in said slots, each con-

ductor traversing the top of $\frac{m}{2n}$ slots and the bottom of a different $\frac{m}{2n}$ slots, and also 25 traversing $\frac{m}{2n}$ slots at $\frac{1}{2n}$ th of the slot depth and $\frac{m}{2n}$ slots at $\frac{2n-1}{2n}$ th of the slot depth and so on through all of said m slots, 30 whereby the self-inductance of all of said conductors is rendered substantially equal.

In testimony whereof, I have hereunto subscribed my name this 14th day of April, 1913.

JAN ARTHUR KUYSER.
